OIL TEMPERATURE REGULATOR

Allan C. Hoffman, Dayton, Ohio, assignor to
 United Aircraft Products, Inc., Dayton, Ohio,
 a corporation of Ohio

Application June 14, 1944, Serial No. 540,173

5 Claims. (Cl. 257—128)

1
 This invention relates to oil temperature regulators or like devices used in the cooling of a congealable liquid circulated under conditions of heat and pressure, as in a lubrication system for aircraft engines. More particularly, the invention is concerned with means for obtaining a rapid loosening and decongealing of packed oil in order that the regulator may be quickly conditioned for flow therethrough upon starting of the engine. The invention has special reference to oil temperature regulators of the jacketless type.

Heretofore, in commercially feasible jacketless oil temperature regulators, the oil has been caused to flow either through the cooling passage defined by the core or through an alternative conduit bypassing the oil with respect to the cooling passage, the oil when flowing through the alternative conduit being out of heat exchange relationship with the congealed oil in the core. Accordingly, prior art devices relied upon pressure alone to remove restrictions from the cooling passage, or upon a combination of pressure and injection of hot oil directly into the congealed mass, no utilization being made of the warming effect of the flowing oil in the by-pass.

An object of the invention is to obtain a quick warm-up of congealed oil in the core by permitting the by-passing oil to flow in heat exchange relation with the oil in the core.

Another object of the invention is to incorporate a part of the oil by-pass in the core, preferably in the sections of the core nearest the outlet thereof, in such manner that congealed oil in the core is restored to fluidity by heat exchange with the by-passing oil and the pressure required to clear a path in the core steadily is reduced.

A further object is to obtain a generally new core construction for oil temperature regulators, a feature of which is a centrally located tank with first and second conduit means leading respectively from the regulator inlet to the tank and from the tank to the core inlet, and a third or by-passing conduit means leading directly from the tank to the regulator outlet, all of the conduit means being disposed within the core in heat exchange relation with the oil therein.

Other objects and structural details of the invention will appear from the following descrip-

2
 tion when read in connection with the accompanying drawings, wherein:

Fig. 1 is a view, partly in front elevation and partly in cross section, of an oil temperature regulator embodying the present invention, being taken substantially along the line 1—1 of Fig. 2; and

Fig. 2 is a view in longitudinal section of the regulator of Fig. 1, the longitudinal air flow tubes being omitted, and being taken substantially along the line 2—2 of Fig. 1.

Referring to the drawings, an oil temperature regulator of the class to which this invention relates comprises a cylindrical shell 11 encasing a core made up of a plurality of longitudinally extending spaced partitions 12, and heat exchange tubes 13 (Fig. 1) filling the spaces between the partitions. The ends of the tubes 13 are expanded to a polygonal shape and occupy a nested relation with respect to each other, the arrangement being such that at the opposite ends of the core the tubes present a closed front while intermediate their ends within the shell 11 the tubes are spaced apart and define a maze for the passage of the oil which flows to and from the core through radial openings in the shell. To hold the tubes 13 in assembled relation, and as a seal against the escape of oil from the core, the tube ends are secured together by a soldering operation. Similarly, the core is rigidly connected to the inner surface of the shell by means constituting a seal and a bond. The tubes 13 are open throughout their lengths for the passage therethrough of a coolant which may be fluid in any form. Conventionally, oil temperature regulators for aircraft are disposed in an air stream which passes through the core tubes, cooling the tubes and thereby the surrounding oil in the shell.

Secured to the external surface of the shell 11, and, in effect, forming an integral part of the shell, is a fitting 14. The undersurface of fitting 14 is recessed to provide separate fluid chambers, while the upper surface of the fitting is formed with three longitudinally spaced vertical ports, 15, 16 and 17, (see Fig. 2) opening into internal fluid chambers. Port 15 and a fluid chamber 18 overlie a longitudinal row of vertical tubular conduits 19, having ends projecting through the shell 11 and which extend inward toward the center of the

regulator core. The inner ends of the tubular conduits 19 terminate in a tank-like enclosure 21 longitudinally disposed in the core near the mid portion thereof. Similarly arranged, and, for the sake of convenience of construction, being disposed as a continuation of the row of tubular conduits 19, is a series of tubular conduits 22 having their outer ends projecting into a fitting chamber 23 beneath port 16 and having their inner ends in the tank 21. The rows of conduits 19 and 22 are combined into a single radial row, the several elements of which are divided by a fitting rib 24 into groups of approximately equal number communicating with separate fluid chambers in the fitting. The arrangement is such that fluid entering the fitting 14 by way of one port 15 or 16, may flow from the fitting to the tank 21 and then back to the fitting and out the other port 15 or 16 without entering the cooling passages of the core, although passing in heat exchange relation with the oil therein. Formed as extensions of the row of tubes 19 and 22, and having their inner ends projecting into the opposite side of the tank 21, is a row of tubular conduits 25. The conduits 25 lead radially outward to a chamber 26 formed within the shell 11 through the cooperation of end sections 27 and a cover plate 28. An opening 29 in the plate 28 communicates the chamber 26 with the core. Thus, oil introduced into the tank 21, as by the conduits 19, may not only enter the direct return conduits 22 but also may pass through the row of tubular conduits 25 to chamber 26 and from there begin a travel through the cooling passages of the core.

Under the influence of continuously applied pressure the oil may progress through the core back toward the fitting 14, and, in so doing, contact successive air flow tubes 13 and be cooled. The partitions 12 serve as baffles for the oil and preferably have end openings 30 (Fig. 1) similar to the opening 29 to permit the passage of oil therethrough, the openings in adjacent baffles being staggered in such manner as to cause the oil to move in a tortuous path from end to end of the core. The exit from the core is defined by two radial openings 31 and 32, in the shell 11 (see Fig. 1), which openings register with fluid passages 33 and 34 in the fitting 14. The passages 33 and 34 communicate with the fitting port 17 and are defined by a longitudinal rib 35 which occupies a position astride tubular conduits 22.

The tubular conduits 19 and 22 and the extensions 25 thereof occupy positions substantially in the center of the core, the channel from which they displace the air flow tubes 13 being closed at the ends by bars 36 having a U shape in cross section. Although the invention is not limited to any particular manner of mounting the tank-like enclosure 21, this tank preferably has a length coincident with the length of the core. Thus openings may be provided in the channel bars 36 for the ends of the tank 21 or, as shown, the bar at each end of the core may be made in two sections, the adjacent ends of which abut the top and bottom of the tank. The assembly comprising the channel bars 36 and the tank 21 is made a fixed part of the core, the elements of the assembly being soldered to each other, and to the ends of the adjoining air flow tubes 13.

In order that the flow of the oil through the regulator may be controlled in accordance with the temperature and viscosity conditions thereof, there is customarily mounted on the fitting 14 a manifold head embodying valves constructed and

arranged to compel the oil to flow through the core, or to permit a flow in by-passing relation to the core—a by-passing flow being initiated when the oil is not in need of cooling or when congelation in the core interferes with the flow therethrough in a manner tending objectionably to raise the pressure in the system. Any known manifold head for performing these functions may be used in conjunction with the core construction here disclosed. The manifold head illustrated is one disclosed and claimed in a prior patent application by Walter H. Geddes and Phillip W. Schanke, Serial No. 514,300, filed December 14, 1943. Briefly described, the head comprises a body portion 37 having openings 38 and 39, respectively constituting the regulator inlet and the regulator outlet. To the inlet 38 is connected a line through which heated oil flows under pressure after its passage through the engine. To the outlet 39 is connected a line returning the cooled oil to the reservoir where it is held and withdrawn as required for re-use in the engine. Entering the manifold head by way of opening 38 the oil flows into a chamber 41 and into contact with a thermostat 42 forming a part of an assembly further comprising valves 43 and 44 respectively controlling ports 45 and 46. A spring 47 normally holds the thermostat and valve assembly in a position closing the port 45 and opening port 46. Accordingly, the oil in chamber 41 may pass through port 46 to a chamber 48 communicating with outlet 39 (see Fig. 1). In response to a rising oil temperature the thermostat 42 operates to withdraw valve 43 from its seat in port 45 and simultaneously to move valve 44 into a position closing port 46. Now the oil in chamber 41 may pass through port 45 and into a chamber 49 overlying and communicating with fitting port 15. Thus oil permitted to enter chamber 49 in the manifold head is allowed to continue its flow into the regulator by way of port 15 and chamber 16 in the fitting and thence through tubular conduits 19 into the tank-like enclosure 21. Should oil in the tank 21 flow upward through the parallel group of tubular conduits 22 to fitting chamber 23 and port 16, it returns into a chamber 51 in the manifold head. The chamber 51 is connected by means of a port 52, a chamber 53, and another port 54 with the outlet chamber 48. Flow from the chamber 51 to the outlet through port 52 is controlled by a valve 55 forming part of a thermostat assembly 56. Under relatively cool oil temperatures the valve 55 occupies an open position with respect to the port 52 but as the temperature of the oil increases, valve 55 moves to a seated position in the port and so closes the by-pass represented by the tubular conduits 22. Chamber 53, wherein the thermostat of assembly 56 is stationed, overlies and communicates with fitting port 17 which is the outlet from the core. Accordingly, oil discharged from the core passes around the thermostat and causes the valve 55 to remain closed so long as the temperature remains at a predetermined value. Surge pressures arriving at the regulator inlet 38 are dissipated by allowing the valve 44 to move through and beyond the port 46, thereby opening the direct connection between the inlet 38 and outlet 39 irrespective of the temperature of the oil. Also, the thermostat assembly 56 is adapted to yield to a pressure of predetermined value applied to the face of the valve 55. Thus, even though the valve 55 is held closed by the thermostat the attainment of a predetermined pressure in the tank 21 and in the

communicating fitting chamber 51 will result in an unseating of the valve and a consequent opening of the by-pass through the tubular conduits 22. Reverse flow from the outlet chamber 48 to the thermostat chamber 53 is prevented by a check valve 57.

In the operation of the system when the engine is started with oil packed around the air flow tubes 13 as a result of congelation, flow through the core is obstructed. At the start of the circulation of the oil direct flow between the inlet 38 and outlet 39 takes place through the open port 46, surge pressures being denied access to the core by the closed valve 43. As operation of the engine warms the oil, thermostat 42 responds by closing port 46 and moving valve 43 to open position to permit the oil stream to enter chamber 48 and fitting inlet port 15. Passing through the tubular conduits 19 to tank 21 the oil finds the easiest path of continued flow to be back through conduits 22 to fitting port 16 and into chamber 51 and through the open port 52 to chamber 48 and the outlet. The flow so established continues until a further rise in oil temperature causes valve 55 to be moved to a position closing port 52. The entire fluid flow then is compelled to pass from tank 21 downward through the tubular conduits 25 to chamber 26 and thence through the opening 29 to the core. There a combination of heat and pressure loosens and expels any remaining congealed oil and re-establishes flow through the core. It will be understood that in the course of the by-passing flow through conduits 19, tank 21 and conduits 22, the heat of the flowing oil is transmitted to the congealed oil in the core and has a warming, decongealing effect thereon. Also, a continuous pressure is maintained through the conduits 25 on the oil in the core, attempting to move it to the outlet. Gradually, as first the core section nearest the outlet and then successive sections away from the outlet are decongealed by the conduction of heat from the conduits 19 and 22, the pressure required to re-establish flow through the core is reduced until it drops below the value necessary to obtain a relief opening of valve 55. At this point the pressure of the oil in the tank 21 is sufficient to maintain flow through the tubular conduits 25 and through the core of the regulator, but is insufficient to force open the valve 55 and permit a by-pass flow through the tubular conduits 22.

Modifications of the invention, and uses thereof in connection with oil temperature regulators of the other classes, are possible.

What is claimed is:

1. In an oil temperature regulator or like device for the cooling of a congealable liquid which is heated and circulated under pressure, an assembly of tubes having their medial portions spaced apart permitting a flow therearound of the liquid to be cooled, said tubes being arranged for the passage therethrough of a coolant whereby the temperature of said liquid is modified through heat exchange, a casing enclosing said tube assembly, means defining in conjunction with a portion of said casing a liquid chamber communicating with the interior of said assembly, an outlet from said assembly, means constituting respectively the regulator inlet and the regulator outlet the latter communicating with the outlet from said assembly, a tank-like enclosure within said tube assembly, and a plurality of conduit means in communication with said tank-like enclosure and passing through said assembly without com-

municating therewith, a first one of said conduit means extending from said regulator inlet to said tank-like enclosure, a second one of said conduit means extending from said tank-like enclosure to said assembly inlet, and a third one of said conduit means extending from said tank-like enclosure to said regulator outlet.

2. In an oil temperature regulator or like device for the cooling of a congealable liquid which is heated and circulated under pressure, an assembly of tubes having their medial portions spaced apart permitting a flow therearound of the liquid to be cooled, said tubes being arranged for the passage therethrough of a coolant whereby the temperature of said liquid is modified through heat exchange, a casing enclosing said tube assembly, means defining in conjunction with a portion of said casing on one side of said assembly a liquid chamber communicating with the interior of said assembly, an outlet from said assembly, means oppositely disposed with respect to said assembly inlet chamber and constituting respectively the regulator inlet and the regulator outlet the latter communicating with the outlet from said assembly, a tank-like enclosure mounted within said tube assembly, a first series of tubular conduits interconnecting said regulator inlet and said tank-like enclosure, a second series of tubular conduits interconnecting said regulator outlet and said tank-like enclosure, and a third series of tubular conduits interconnecting said tank-like enclosure and said assembly inlet.

3. An oil temperature regulator or like device according to claim 2, characterized in that said first and second series of tubular conduits are combined into a longitudinal row of conduits, some of which have their one ends in communication with said regulator inlet and the others 40 of which have their corresponding ends in communication with said regulator outlet and all of which conduits have their opposite ends extending into said tank-like enclosure, and said third series of tubular conduits projecting from said tank-like enclosure as extensions of said first and second series of conduits.

4. A core construction for oil temperature regulators, comprising an assembly of tubes having their medial portions spaced apart for a flow therearound of the oil, said tubes being arranged for the passage therethrough of a coolant whereby the temperature of the oil is modified by heat exchange, means defining an inlet to said tube assembly at one side thereof, a tank-like enclosure within said tube assembly and forming a part thereof, a first series of tubular conduits extending radially inward in said tube assembly, the inner ends of said conduits terminating within said tank-like enclosure, a second series of conduits having their one ends within said tank-like enclosure and extending radially outward into communication with said tube assembly inlet, and means dividing said first series of tubular conduits into two groups of conduits whereby oil may be delivered to said tank-like enclosure through one group of conduits of said first series and may leave said tank-like enclosure alternatively by way of the other group of conduits of said first series or by way of the conduits of said second series.

5. An oil temperature regulator of the jacketless type, comprising an assembly of heat exchange tubes, a casing surrounding said tube assembly, means including a portion of said casing defining a header chamber communicating with

said tube assembly, an opening in said casing defining an outlet from said tube assembly, a tank within said tube assembly, and a plurality of independent conduits passed through said tube assembly and connecting said tank to the exterior of said casing and to said header chamber, said conduits providing inlet means to the tank and by-pass means for oil which by reason of congealation within the tube assembly is unable to leave the tank by way of said header chamber. 10
